UNITED STATES PATENT OFFICE.

LESTER E. VAN HISE, OF LOS ANGELES, CALIFORNIA.

GAS-ENGINE.

1,284,826.

Specification of Letters Patent. Patented Nov. 12, 1918.

Application filed April 20, 1914. Serial No. 833,044.

To all whom it may concern:

Be it known that I, LESTER E. VAN HISE, a citizen of the United States, residing at Los Angeles, in the county of Los Angeles 5 and State of California, have invented certain new and useful Improvements in Gas-Engines, of which the following is a specification.

This invention relates to improvements in 10 internal combustion engines and particularly to that type of engine in which an impulse from the combustion of the fuel may be had at every stroke of the piston or pistons.

15 It is an object of the invention to provide an internal combustion engine with a piston which is capable of compressing air outside the combustion chamber, some of which is employed, first for scavenging the said 20 chamber and then for carrying a compressed explosive mixture into said chamber, a valve mechanism being employed for controlling the movement of the compressed materials.

It is a further object of the invention to 25 provide a gas or internal combustion engine with an air compressing chamber outside the combustion chamber and a mixing chamber also outside the combustion chamber, the piston of the engine being capable of 30 compressing air in said chambers both for scavenging the combustion chamber and for introducing air mixed with fuel for securing proper explosions within the combustion chamber.

35 With these and other objects in view, the invention comprises certain novel constructions, combinations and arrangements of parts, as will be hereinafter fully described and claimed.

40 In the accompanying drawing forming a part of this specification:

Figure 1 is a vertical central sectional view through an engine constructed in accordance with this invention, the plane of 45 the section extending through the chambers in which the air is compressed by the piston.

Fig. 2 is a vertical central sectional view through said engine taken upon a plane at right angles to that of Fig. 1.

50 Fig. 3 is a horizontal sectional view taken upon the line 3—3 of Fig. 1.

Fig. 4 is a detail view showing the carbureter in top plan view and the spraying nozzle extending tangentially therefrom.

55 The engine of the present invention is pro-

vided with chambers which communicate with the combustion chamber, the piston being adapted to compress air in said chambers before it is admitted to the combustion chamber, a single valve controls the inlets 60 from said chambers into said combustion chamber. The engine is a two-cycle engine in action receiving an explosion and an impulse therefrom at every reciprocation of the piston. In the accompanying drawing the 65 preferred structure of the engine has been disclosed and the details and features thereof will now be more specifically described, reference being had to said drawing. In said drawing 5, indicates the combustion chamber and power cylinder of the engine; 6 a tandem cylinder of larger diameter than the cylinder 5. A piston 7 moves in the cylinder 5 and is provided with an enlarged portion 8 forming a piston for the enlarged cylinder 6. The cylinders 5 and 6 are mounted upon a suitable framing 9 within which are guides 10 for directing the movement of a cross-head 11. The cross-head 11 is rigidly secured to the lower end of a piston rod 12, 70 the upper end of which is fastened in the upper end of the piston 7. The lower end of the cylinder framing usually rests upon a plate 13, through which the piston rod 12 passes. A packing gland 14 is provided in 75 said plate 13 and surrounds the piston rod 12 so as to prevent the leakage of air about the same.

The cross-head 11 is pivotally connected with a pitman 15 which extends to and is 80 journaled upon a bearing 16 formed upon the engine crank 17. The crank is formed in the crank shaft 18 which is journaled in the framing 9. The lower end of the cylinder 5 is provided with a series of exhaust 85 outlets 19 which communicate with an exhaust passage 20 formed in the casing of the cylinder. The passage 20 is adapted to lead exhaust charges into an exhaust outlet pipe 21. The piston 7 controls the said exhaust 90 outlets or ports 19. The cylinder 5 is also usually provided with a water jacket 22 for keeping it cool. The cylinder casing is further provided with passages in which air is compressed, one of said passages as 23 usually extending up one side of the engine 100 while the other passage as 24 extends up the other side thereof.

The lower end of the passage 23 communicates with the lower end of the cylinder 6 110

and the lower portion of said passage is also enlarged and extended entirely or part way around the cylinder 6 to form an annular passage around the same. The upper 5 end of said passage 23 is controlled by a rotating valve 25 mounted at the upper end of the combustion chamber and when said valve is in the proper position therefor, air may escape from the passage 23 into said 10 combustion chamber.

The passage 24 communicates with the upper end of the cylinder 6 and extends therefrom to the valve 25 where it may be allowed to discharge its compressed charges into the 15 combustion chamber upon the rotation of said valve.

In order to provide the necessary fuel for the internal combustion of the engine, a carbureter 26 of any desired type is employed 20 and provided with an inlet pipe 27 by which gasoline or other fuel is admitted thereto. A valve 28 controls the flow of fuel into the carbureter, said valve being operated by the usual float 29. A spraying nozzle 30 ex 25 tends from the carbureter into the upper end of the passage 24. The said nozzle as shown in Fig. 4 is usually arranged tangentially of the carbureter casing so that a needle valve 31 moving therein and controlling the dis 30 charge of gasoline through the nozzle may project outside the casing and be engaged by a cam 32 for securing its proper operation. The cam 32 is carried by a shaft 33, which may be turned by any suitable means (not 35 shown in the drawings) under the control of the operator. A spring 34 normally forces the needle valve 31 against the said cam 32. The inner end of said nozzle 30 discharges gasoline or other fuel into the 40 passage 24 under the action of the air compressed in said passage, when the valve 25 connects the passage 24 with the combustion chamber.

In order to equalize said pressure with 45 respect to the carbureter a by-pass pipe 35 extends from the passage 24 to the top of the carbureter casing so as to communicate with the carbureter above the surface of the fuel therein. A throttle valve 36 is mounted 50 transversely of the upper end of the passage 24 so as to control the mixture which enters the combustion chamber. Said throttle valve is usually a rod having a half round portion adapted to rock across the upper end 55 of said passage 24. The outer end of said rod is provided with an arm 37 with which is connected an operating wire or rod 38 which may be extended to a point within easy reach of the operator.

60 The upper portion of the combustion chamber casing is provided with an opening 39 in its walls which is adapted to receive the usual spark plug 40 for igniting the gaseous charges in the combustion chamber.

65 Air is admitted to the cylinder 6 from the

atmosphere through an opening 41 arranged about midway of the length of said cylinder. The said opening 41 is covered by a valve casing 42 in which is seated a valve 43. The stem 44 of the said valve extends outside the casing and a spring 45 surrounding the same normally tends to seat the valve. The said valve is opened for the inlet of air under the suction produced by the movement of the piston 8.

The valve 25 is preferably made tapering as clearly shown in Fig. 2 and rotates in a tapering valve seat 46 mounted at the upper end of the cylinder 5. One side of the sail valve is cut away at 47 to form a port which 80 is capable of connecting the upper ends of the passages 23 and 24 successively with the upper end of the combustion chamber 5. The valve 25 is carried by a valve stem 48 suitably journaled in the casing and provided with a collar 49 adapted to bear upon the valve casing so as to prevent an outward movement of the valve stem. The valve proper 25 has a splined engagement with the shaft 48 so that while it will be turned by 90 the rotation of the valve stem, it will be capable of being forced against the tapering seat 46 by a spring 50, interposed between the collar 49 and the adjacent end of the valve 25. The valve is thus always kept 95 tightly against its seat and made less likely to collect carbon so as to permit leakage. The shaft 48 may be mounted upon the ball bearings as at 51 if desired.

The valve 25 is made to rotate in unison 100 with the crank shaft 18 and at the same speed and in order to drive the said valve 25, a connecting shaft 52 is interposed between the crank shaft 18 and the valve shaft 48 and sets of intermeshing beveled gears as at 105 53 and 54 and at 55 and 56, are employed to connect the said shafts, as clearly shown in Fig. 2 of the drawing. It is preferable to inclose the bevel gears in housings, the gears 53 and 54 being covered by the housing 57 110 while a housing 58 incloses the gears 55 and 56. A connecting casing 59 joins said housings and incloses the connecting shaft 52. This shaft 52 also finds bearings in said housings and casing. It will be evident that 115 the rotation of the shaft 18 will thus communicate a corresponding movement to the valve shaft 48.

The operation of the engine will be readily understood in connection with the above description. After the explosion in the combustion chamber, the piston 7 and the larger piston 8 carried thereby will compress the air in the cylinder 6 and force it into the chamber 23 where it will be held by the valve 120 25 until the exhaust ports 19 have been uncovered by the piston 7. As soon as the said exhaust ports are uncovered, the valve 25 will have reached a position where the upper end of the passage 23 will be uncovered 130

and the air compressed therein be allowed to rush into the upper end of the cylinder 5. The air will thus force all of the spent gases from the cylinder and into the exhaust outlet, thoroughly scavenging the cylinder and leaving only fresh pure air therein. As the piston 8 passed the valve 43, it began to draw in the air from the atmosphere behind it so as to fill the upper part of the cylinder 6 again. The up stroke of the piston will cause the air thus drawn into the cylinder 6 to be highly compressed in the small passage 24 and thus be prepared for rushing into the combustion chamber as soon as the valve 25 will permit. The upward stroke of the piston of course, closes the exhaust ports 19, and since the small amount of air in the cylinder 5 will not be compressed to anything like the same degree as the air in the larger cylinder 6, there will be a great difference between the compression in the passages 24 and the upper end of the combustion chamber. As soon as the piston nearly reaches the upper end of its stroke, the valve 25 will connect the passage 24 with said cylinder and the highly compressed charge in said passage will rush into the cylinder 5 carrying with it the sprayed gasoline or other fuel which will at that time be drawn from the nozzle 30 of the carbureter. Before the piston 7 quite reaches the top of its stroke, the valve 25 will close the top of the cylinder 5 and the charge will be fired by the spark plug. Upon the downward movement of the piston under the effect of firing the gaseous mixture, the operation just described will be repeated again. It will be evident that there is no chance for the exhaust gases to remain in the cylinder 5 and the cylinder will not only be quickly and thoroughly cleared of such gases, but will be somewhat cooled by the in-rushing fresh air from the passage 23, leaving the cylinder in good condition for the next firing charge. As the piston 8 passes the valve 43 in its upward stroke, air will be drawn into the lower portion of the cylinder 6 whereby there will always be an ample amount of air below the piston for compression in the passage 23. The by-pass pipe 35 equalizes the pressure with respect to the carbureter so that the gasoline will be properly fed from the nozzle when the compressed air rushes into the cylinder 5, the gasoline being also thoroughly and properly controlled by the float 29 and its valve 28. In practice the small amount of suction produced in the passage 24 when the piston 8 is making its descent in the upper half of the cylinder 6, is found not to disturb the action of the carbureter and if any gasoline from the nozzle is drawn into the upper end of the passage 24, it will simply be commingled more thoroughly with the air of the inrushing charge. The continual use of fresh atmospheric air in the

passages 23 and 24 also assists in keeping down the temperature of the engine. The throttle valve 36 and the cam shaft 33 being under the control of the operator of the engine at all times, makes it possible to 70 readily adjust and control the richness of the mixture which is admitted to the combustion chamber. It will be evident that many of the minor details of the mechanism may be varied and mechanical equivalents 75 thereof employed, without departing in the least from the spirit of the invention.

What is claimed is:

1. An internal combustion engine comprising a cylinder, a piston having an extension portion capable of compressing air outside the combustion chamber upon each stroke thereof, the engine having air receiving passages outside the combustion chamber, one of said passages having means for 80 introducing fuel connected therewith and leading to the outer valve controlled end thereof, the said piston extension operating, first by scavenging the combustion chamber with the air compressed on one stroke, and 85 then for carrying a charge of an explosive mixture with the air compressed on the other stroke, for operating the engine, and a valve operating in conjunction with the movement of the piston for controlling the entrance of 90 said compressed air to the combustion chamber.

2. An internal combustion engine having a cylinder, a piston in said cylinder and arranged to receive an impulse from the 100 firing of an explosive charge upon one stroke, said piston having an enlarged portion for compressing air for scavenging the cylinder upon the same stroke, a storage chamber within which the air may be compressed, said storage chamber being arranged to receive air compressed by the said enlarged portion of the piston and to deliver it into the outer end of the combustion chamber, the said enlarged portion of 105 the piston also being capable of compressing air upon its other stroke and causing it to carry and mix with it fuel for charging the combustion chamber of the engine with an explosive mixture, means for delivering 110 fuel to said compressed air to form said explosive mixture, a valve for positively controlling the admission of compressed charges to the combustion chamber and means for operating said valve in accordance with the movement of the piston.

3. An internal combustion engine having a piston, a cylinder having storage chambers outside the combustion chamber, the said piston being capable of compressing air in 115 one of said storage chambers upon one stroke for scavenging the combustion chamber of the engine, and capable upon the other stroke of compressing air and forcing the same through the other storage chamber 120

having fuel introducing means connected therewith, means for delivering fuel into said chamber, whereby charges of air and explosive materials will be delivered into 5 the combustion chamber of the engine and a single valve arranged to admit explosive and scavenging charges successively upon each reciprocation of the piston.

4. A gas engine comprising a cylinder 10 affording a combustion chamber at one end of the engine piston, a piston moving therein and having an enlarged extension outside the combustion chamber for compressing air, a chamber adjacent to the cylinder 15 for receiving compressed air, a valve for directing the air into the inlet end of the cylinder after each explosion therein, the engine being also formed with a second chamber connected with the inlet end of the 20 cylinder and adapted to receive a charge of compressed air, means for introducing an explosive material into said second chamber, the valve being also capable of directing 25 said explosive material into the combustion chamber, and means for controlling the movement of the valve from the piston and crank shaft.

5. An explosive gas engine having cylinders in tandem, a piston operating partly 30 in one cylinder and partly in the other, one cylinder being adapted for use as a combustion chamber, while the other cylinder is employed for compressing charges of air, a valve for introducing air into the said 35 latter cylinder, separate passages for receiving charges of air from the compressing cylinder, means for introducing an explosive material into one of said passages and a valve interposed between the said passages 40 and one end of the combustion chamber whereby compressed air may be introduced into the combustion chamber first for scavenging the same, and second for carrying an explosive mixture into the same.

45 6. An explosive gas engine having tandem cylinders of different diameters, a piston having portions of large and small diameters for fitting into said tandem cylinders, means for introducing air into one of said 50 tandem cylinders, the piston operating therein being capable of compressing the air in one cylinder and delivering charges thereof into the other cylinder, means for introducing fuel material into one of said 55 charges and a rotating valve having a port capable of directing a scavenging charge of

pure air into one of the cylinders and then of delivering a charge of an explosive mixture into said cylinder and means for firing said charge, the engine having passages for 60 transferring the air from one cylinder to the other.

7. An explosive gas engine having upper and lower cylinders, the upper cylinder being formed with a combustion chamber at 65 one end thereof, while the other cylinder is provided with an air inlet, a valve for controlling said air inlet, the engine casing being provided with passages leading from the lower cylinder to points adjacent the 70 combustion chamber of the upper cylinder, means for admitting fuel to one of said passages, a rotating valve for controlling the same, the upper cylinder being also provided with outlet ports controlled by a 75 piston moving in said cylinder, a piston, and driving connections for controlling said valve connected with the crank shaft of said engine, whereby its movement will be regulated in accordance with the movement of 80 the engine's pistons.

8. In a two-cycle engine having tandem cylinders, the power cylinder of which is of less diameter than the other cylinder, a tandem piston having portions fitting in said 85 cylinders, the engine casing being provided with compression receiving chambers outside the combustion chamber, one being connected with one end of the larger cylinder, while the other is connected with the other 90 end of said larger cylinder, a valve controlling the inlet of air to the larger cylinder, the smaller cylinder having outlet ports for exhaust materials, a carburetor, a valve controlled nozzle adapted to lead mixture 95 enriching materials into one of said compression chambers, a throttle valve controlling the passage of mixtures from one of said compression receiving chambers and a valve common to both said compression receiving chambers and one end of the power cylinder whereby the compressed charges may be alternately directed into said cylinder whereby the cylinder may be first scavenged and then re-charged with explosive 100 material.

In testimony whereof I have hereunto set my hand in presence of two witnesses.

LESTER E. VAN HISE.
